UNITED STATES PATENT OFFICE.

ARTHUR P. JACKSON, OF PASSAIC, NEW JERSEY.

DESIGN FOR A DISPLAY-STAND.

No. 38,619.

Specification for Design.

Patented June 11, 1907.

Application filed April 25, 1907. Serial No. 370,334. Term of patent 14 years.

To all whom it may concern:

Be it known that I, ARTHUR P. JACKSON, a citizen of the United States, and a resident of Passaic, in the county of Passaic and State of New Jersey, have invented a certain new, original, and ornamental Design for a Display-Stand, of which the following is a specification.

The accompanying drawing is a view in perspective of a display stand having my design applied thereto.

What I claim is:—

The ornamental design for a display stand, as shown.

ARTHUR P. JACKSON.
